ERASING ATTACHMENT FOR TYPEWRITERS

Louis Wilner, New York, N. Y.

Application March 25, 1936, Serial No. 70,735

4 Claims. (Cl. 197—181)

This invention relates to typewriters and other writing machines or adding machines and refers more particularly to an erasing device for typewriters.

5 An object of the present invention is the provision of a simple and effectively operable mechanism for obliterating improperly written type characters, which mechanism may be conveniently incorporated in a typewriting machine of 10 any standard make.

Another object is the provision of a typewriting machine having an attachment, through the use of which errors in typewriting may be quickly and easily corrected by erasure while 15 the paper remains in position on the machine.

A further object of the present invention is the provision of an erasing device which constitutes an integral part of the typewriting machine, and which is automatically operable by 20 the depression of a key to move backward the platen carrying the paper and thereupon to move an eraser over the letter or character to be obliterated.

The above and other objects of the present 25 invention may be realized through the provision of an eraser removably mounted upon a rod and pressed by resilient means against the paper carried by the platen.

The rod is reciprocated in the vertical direction by the depression of a key constituting a 30 part of the keyboard of the typewriter, the eraser carried by the bar being passed over a typed character in the course of this vertical reciprocatory movement and obliterating the same. Preferably, the vertical bar contacts a lever in 35 the course of its upward movement which actuates the back spacer of the typewriter, so that before the eraser is brought into contact with the paper the platen is automatically moved one 40 space backward, thus placing the letter to be erased directly in the path of the eraser.

The invention will appear more clearly from 45 the following detailed description when taken in connection with the accompanying drawings, showing, by way of example, a preferred embodiment of the inventive idea.

In the drawings:—

Figure 1 shows in front elevation a typewriter 50 provided with erasing device;

Figure 2 is a section along the line 2—2 of Figure 1, with parts broken off.

Figure 3 is a front elevation of the erasing attachment on a larger scale with some parts 55 broken away;

Figure 4 is a section along the line 4—4 of Figure 3;

Figure 5 is a top view of the device illustrated in Figure 3;

Figure 6 is a perspective view of the vertical bar carrying the eraser;

Figure 7 is a section through the portion of the bar carrying the eraser;

Figure 8 is a top view of the back spacing mechanism;

Figure 9 is a section along the lines 9—9 of Figures 8 and 10;

Figure 10 is a side view of the back spacing mechanism.

The typewriter illustrated in the drawings is 15 a standard construction. This typewriter is shown merely by way of example, since the erasing attachment constituting the subject-matter of the present invention may be used in connection with typewriters of any type or make.

The illustrated typewriter comprises a frame 10 carried by the supports 11 and provided with the movable carriage 12. The platen 13 which is movable along with the carriage is mounted on brackets 14 and 15 and may be rotated by 25 means of the handle 16. The carriage is provided with roller clamps 17 and 18 which press the paper against the platen, and with the line spacer 19. A paper rest 20 constitutes a part 30 of the carriage and surrounds the lower portion of the platen 13. The carriage 12 is movable along with its support 21 which is guided by the guide bars 22 rigidly attached to the frame.

The typewriter ribbon 23 is carried by the ribbon spools 24 and 25 which are mounted upon pivots 26 and 27 carried by the horizontal bars 28 and 29, respectively.

A plate or guide 30 for the type bars is attached to the frame of the typewriter and is 40 provided with a suitable slot 31 through which the type carried by a type bar 32 strikes the ribbon 23 situated in front of the paper (not shown) and the platen 13.

A movable ribbon carrier 32 is situated between the platen 13 and the guide 30. The device which moves the ribbon carrier 32 upward so that it is situated in the path of the type when the latter passes through the slot 31 is not shown in the drawings and is of standard 50 make. This device moves the ribbon 23 upward as soon as the operator depresses one of the keys, so that by the time the type reaches the slot 31 the ribbon is situated between the type and the paper covering the platen 13, so that

the type leaves the impression of the ink carried by the ribbon 23 upon the paper.

The typewriter is provided with typing keys 33 carried by the ends of the key levers 34.

5 The key lever 34a (Figure 2) is provided with an ear 35 and is pivotally mounted upon a rod 36. The opposite end of the key lever 34a is connected with a link 37 which is attached to a type bar 38 carrying the type 39 and pivotally mounted upon the pivot 40. Other key levers 34 are similarly constructed.

10 In the normal inoperative position shown in Figure 2 of the drawings the type bars 38 rest upon a support 41 which is rigidly connected with the frame 10, while the key bars 34 rest upon the rod 42 which is also firmly connected with the frame 10.

15 When the key 34a is depressed by the operator, 20 that the key bar 34a swings around its pivot 38 so that the link 37 pushes upward the type bar 38 and thereby moves the type 39 into the slot 31 of the guide plate 30. At the same time the ribbon supporting device 32 is moved upward so that the type 39 strikes the ribbon 23 and leaves an 25 impression upon a sheet of paper which covers the platen 13. Thereupon the carriage 12 and the platen 13 supported thereby are moved one space to the left (looking in the direction of Figure 1) by the mechanism of the usual type 30 which is not shown in the drawings. Finally, the type bar 38 and the key bar 34a are moved back to their original positions illustrated in Figure 2 by resilient means not shown in the drawings.

35 The back space key 42a is carried by one end 35 of a horizontal lever 43 which extends to the rear of the carriage and which is pivoted at 43 (Figure 10). The rear end 41 of the lever 43 is in engagement with an arm 42 (Figure 9) pivoted at 43 and having a projection 44 which 40 engages a slanting surfaces 55 (Figure 8) of the lever 44. The lever 44 is provided with a hook 45 and has a slot 46 through which passes the pivot 47. The depression of the back space lever 43 is transmitted by the projection 44 of the arm 42 to the surface 55 of the lever 44, the hook-shaped end 45 of which is brought into engagement with a rack 48 carried by the movable carriage 12 which supports the platen 13 (Figures 2 and 4). The mechanism actuating the lever 44 causes the hook to carry out an oscillatory movement, in the course of which the carriage and the platen 13 are moved one space to the right (looking in the direction of Figure 1). At the end of this movement the hook 45 is in engagement with an adjacent tooth of the rack 48.

50 The above-described typewriter is of the standard type and does not constitute a part of the present invention.

55 In accordance with the present invention, the typewriter comprises an erasing attachment which constitutes an integral part of the typewriter, and which is actuated by the depression of the key 50 shown in Figures 1 and 2. The key 50 is attached to the vertically bent end of a substantially horizontal key bar 51 provided with a curved middle portion 52 which extends over the support 42. The key bar 51 is provided with an ear 53 extending from the upper side thereof. A pivot 54 passes through the ear 53 so that the key bar 51 is oscillatable around the pivot 54. A second smaller ear 55 is situated on the opposite lower side of the key bar 51 and carries one end of the coil spring 56, the opposite end of which is attached at 57 to the frame 10 of the typewriter. The opposite end of the key bar 51

is pivotally connected at 58 with an ear 59 constituting a part of a vertical eraser bar 60. The bar 60 extends between the vertical portion 60a of the frame 10 and the support 61 carrying the shaft 40 upon which the type bars 38 are rotatably mounted.

5 The vertical bar 60 is provided with a diagonally bent portion 60a and an upper vertical portion 60b extending between the platen 13 and the guide plate 30 at a short distance from the movable ribbon support 32.

10 The upper end of the rod 60 is illustrated on a larger scale in Figures 6 and 7 of the drawings; this end is bifurcated and comprises two substantially flat prongs 62 and 63 separated by a vertical slot 64 and interconnected by the eraser casing 65 which is of trapezoidal form in cross-section, as shown in Figure 7. An eraser 66 is situated in the casing 65 and may be held therein by friction or by any suitable stop not shown in the drawings. The eraser 66 may be of any standard make and is provided with an operative surface 67 which projects beyond the prongs 62 and 63 and which is passed over the surface of the paper by the actuation of the key 50 to erase a typed character. Any suitable abrasive may be used to provide the surface 67.

15 The eraser 66 may be conveniently removed from its casing 65 and replaced by a new one, whenever necessary.

20 As shown more clearly in Figure 3, the eraser is pressed against the platen 13 and the paper covering the same by two leaf springs 68 and 69. The leaf spring 68 presses against the prong 62 while the leaf spring 69 is pressed against the 25 prong 63. The leaf spring 68 is carried by a vertical support 70, the lower end of which is firmly connected with the guide 30. Similarly, the leaf spring 69 is carried by a support 71 which is also attached to the guide 30. The eraser casing 65 30 is guided by the leaf springs 68 and 69 during its movement.

35 The leaf springs 68 and 69 press the prongs 62 and 63 against the platen 13 in all positions of the eraser bar 60. However, in the inoperative 40 position of the device the eraser 66 carried by the casing 65 is situated below the springs 68 and 69 so that the type 39 can pass conveniently through the slot 31 formed in the guide plate 30 and through the slot 54 provided between the bifurcated ends 62 and 63 of the eraser bar 60, thus 45 reaching the ribbon 23 and making an impression upon the paper covering the platen 13.

50 The eraser attachment is operated in the following manner.

55 When the part of the paper provided with the letter or the character to be erased is situated opposite the slot 31 the eraser is actuated merely by pressing upon the key 50. Then the key bar 51 swings upon its pivot 54 so that the vertical 60 rod 60 which is connected by the pivot 58 with the bar 51, is moved upward, thereby extending the spring 56. The eraser 66 carried by the upper 65 vertical end of the rod 60 is moved along with the rod and the operative surface 67 of the eraser is passed over the letter or the character to be erased. The pressure of the eraser 66 against the paper is sufficient to erase the character, since such pressure is caused by the substantially 70 strong leaf springs 68 and 69 which press against the prongs 62 and 63 of the vertical bar 60.

75 After the upward movement of the bar 60 has been completed, the spring 56 pulls the key bar 51 back into the position shown in Figure 2, so 75

that the eraser 66 moves once again over the letter or character to be erased.

In most instances the letter or character is erased completely after the key 50 has been depressed once. It is possible, however, to repeat this operation several times, provided that prior to each actuation of the key 50, the letter or character to be erased is placed in front of the slots 31 and 64.

10 The carriage 12 and the platen 13 move automatically one space forward immediately after a letter or character has been imprinted upon the paper by one of the type levers 38. If at that time the operator finds that an error has been made, the operator has to strike by hand the back space key 42a in order to bring the incorrectly typed character in front of the slot 31. Then the operator strikes the eraser key 50 and thereby erases the incorrectly typed character.

20 In accordance with the present invention, this necessity of operating the back space lever 43 prior to the erasing may be eliminated through the provision of a device which automatically moves the carriage 12 one space back after the 25 eraser key 50 has been actuated and before the eraser 66 moves in front of the slot 31.

This device for automatically moving backward the carriage 12 at the time the eraser key 50 is actuated is illustrated in Figures 3, 4, 5, and 8 30 of the drawings, and comprises a lever 70 having a horizontal portion 70a extending at right angles to the central axis of the platen 13, a vertical portion 70b, another horizontal portion 70c, and a bent end 71a which is situated adjacent the portion 60b of the vertical bar 60. The lever 70 extends to the back of the carriage and is movable around a pivot 72 carried by support 73 which is firmly connected with the frame of the typewriter. As shown in Figures 5 and 8, the lever 70 is provided with a slot 74 through which a pin 75 is passed which is carried by the lever 44.

The lever 70 is actuated by a projection 76 (Figure 3) which is carried by the eraser bar 66, or may constitute an integral part thereof, and which 45 is provided with an inclined surface 77. The surface 77 engages the end 71a of the lever 70 as the bar 66 is moved upwardly in the direction of the arrow 78, thereby causing the lever 70 to turn around its pivot 72. Since the pin 75 connects the lever 70 with the lever 44, the movement of the lever 70 is transmitted to the lever 44 which is provided with a projection 90 engaging an inclined surface 91. The projection 90 will slide along the surface 91 causing the hook 45 of 50 the lever 44 to engage a tooth of the rack 48 and to move the carriage one space backward. This movement is substantially completed before the eraser 66 is moved in front of the slot 31, so that the eraser is brought into contact with the letter 55 or character to be erased.

The projection 76 remains in contact with the lever 70 during substantially the entire movement of the bar 66, so that no further movement of the carriage 12 takes place and no other letters or characters are smeared by the eraser. The projection 76 is moved out of contact with the lever 70 when the bar 66 returns to its original position shown in Figure 3.

70 An important advantage of the present invention is that the erasing attachment constitutes an integral part of the typewriter and is operated by the depression of a key in the same manner in which the other keys are operated. The attachment does not interfere with the usual construc-

tion of the typewriter and requires merely the addition of one key upon the keyboard.

Furthermore, in accordance with the present invention, the necessity of moving the carriage by hand one space back prior to the erasing may be eliminated, since the movement of the eraser bar may automatically actuate the back spacer mechanism and move the carriage one space backward before the eraser is brought into contact with the letter or character to be erased.

What is claimed is:—

1. In a typewriting machine having a frame, means movable relatively to said frame and supporting a sheet of paper, a plurality of types and means causing said types to carry out a striking movement against the first-mentioned means to print a character upon said sheet, the path of movement of the types adjacent the first-mentioned means being the same for all types in relation to said frame; an eraser support having two prongs at one of the ends thereof, a space being formed between said prongs which is situated in said path in the inoperative position of said support, and an eraser casing adapted to contain an eraser and connected with said prongs, said eraser casing being situated outside of said path in said inoperative position of the support; means carried by said frame and engaging at least one of said prongs, the last-mentioned means being adapted to press the eraser contained in said eraser casing against the sheet of paper, means connected with said eraser support to move the same out of its inoperative position, whereby said eraser casing is moved into said path to cause the eraser to erase an incorrectly typed character, and means connected with the last-mentioned means to move said eraser support back into its inoperative position.

2. In a typewriter machine having a frame, means movable relatively to said frame and supporting a sheet of paper, a plurality of types and means causing said types to carry out a striking movement against the first-mentioned means to print a character upon said sheet, the path of movement of the types adjacent the first-mentioned means being the same for all types in relation to said frame; a vertical eraser support having two prongs at the upper end thereof, a space being formed between said prongs which is situated in said path in the inoperative position of said support, and an eraser casing adapted to contain an eraser and connected with said prongs, said eraser casing being situated below said path in said inoperative position of the support, a spring engaging one of said prongs and adapted to press the eraser contained in said eraser casing against the sheet of paper, means connected with said eraser support to move the same upward out of its inoperative position, whereby said eraser casing is moved into said path to cause the eraser to erase an incorrectly typed character, and means connected with the last-mentioned means to move said eraser support downward and back into its inoperative position.

3. In a typewriting machine having typing keys, means supporting a sheet of paper, means moving the first-mentioned means one space forward upon the actuation of each key, and means for moving the first-mentioned means one space backward; a support adapted to carry an eraser, means connected with said support to move the same for the purpose of causing said eraser to pass over the sheet of paper to obliterate an incorrectly typed character, and means connected

with the third-mentioned means and actuated by the moving support to cause the third-mentioned means to move the first-mentioned means one space backward, whereby the incorrectly typed character may be placed in the path of movement of the eraser.

4. In a typewriting machine having a frame, a plurality of typing keys, means supporting a sheet of paper, means moving the first-mentioned means one space forward relatively to said frame upon the actuation of each key, and back spacing means for moving the first-mentioned means one space backward relatively to said frame; a support adapted to carry an eraser, means connected with said support to move the same for the purpose of causing said eraser to

pass over the sheet of paper to obliterate an incorrectly typed character, a lever pivotally mounted upon said frame and operatively connected with the back spacing means, said lever when moved actuating the back spacing means to move the first-mentioned means one space backward, one end of said lever being situated adjacent said support, and a projection carried by said support and engaging said end of the lever while the support is moving to move said lever and thereby cause the back spacing means to move the first-mentioned means one space backward, whereby the incorrectly typed character may be placed in the path of movement of the eraser.
